UNITED STATES PATENT OFFICE.

JAMES M. BREEN, OF PELHAM, NEW YORK, ASSIGNOR TO RADIUM DIAL COMPANY, OF PITTSBURGH, PENNSYLVANIA.

DESIGN FOR A LUMINOUS BEAD.

56,493.

Specification for Design.

Patented Nov. 2, 1920.

Application filed June 14, 1920. Serial No. 389,033. Term of patent 14 years.

To all whom it may concern:

Be it known that I, JAMES M. BREEN, a citizen of the United States, residing at Pelham, in the county of Westchester and State of New York, have invented a new, original, and ornamental Design for Luminous Beads, which may be employed as luminous pendants for lighting-fixtures, of which the following is a specification, reference being had to the accompanying drawing, forming part thereof.

The accompanying drawing illustrates a bead embodying my ornamental design.

The body of the bead has a cylindrical shape with one end rounded and having a cap on its other end and said cylindrical body is made luminous in appearance by luminous material contained therein.

I claim:

The ornamental design for a luminous bead as shown.

JAMES M. BREEN.
